JOURNAL BOX PACKING

Charles T. Ripley, Wilmette, Ill.

Application January 25, 1935, Serial No. 3,433

1 Claim. (Cl. 308—88)

This invention relates to a new and improved journal box packing, more particularly to an improved form of packing material or packing units, and the method of using same within a car journal box in order to supply lubricant to the journal.

The usual method of packing a car journal box is to force a quantity of loose cotton or woolen waste into the space between the bottom of the journal box and the exposed lower surface of the journal, and to saturate this waste with oil. The waste may be provided with metal springs embedded therein and distributed therethrough for keeping the packing in contact with the journal. The oil-soaked waste rubs against the lower surface of the rotating journal thus maintaining the requisite film of oil between the upper side of the journal and the brass which supports the box and the load carried thereby.

There are several objections to this form and method of packing, the most serious fault being the frequent occurrence of "waste-grabs", that is small fluffy particles of the waste material are carried up by one side of the rotating journal and eventually some of this material finds its way between the journal and the brass and breaks down the oil film, often resulting in the burning out of the bearing and other serious damage.

According to the present invention, the oil-carrying material, the waste with the springs embedded therein, is enclosed in an envelope or bag (or a plurality or series of envelopes) of flexible fabric which is porous to allow the passage of oil therethrough but is of fine enough texture, that is without large openings, so that it will effectively hold the waste. The oil is transmitted through this envelope to the journal, but the fine particles of the waste are confined and do not ride up on the journal, thus eliminating the principal source of waste-grabs. The springs keep the waste open and loose against matting and in contact with the upper surface of the envelope and the envelope in contact with the journal. This form of packing has numerous other advantages as will be brought out hereinafter.

The principal object of this invention is to provide an improved journal box packing of the type briefly described hereinabove and disclosed more in detail in the specifications which follow.

Other objects and advantages of this invention will be more apparent from the following detailed description of one approved form of packing and the method of using same according to the principles of this invention.

In the accompanying drawing:

Fig. 1 is a longitudinal vertical section through a standard type of railway car journal box with the improved packing used therein.

Fig. 2 is a transverse vertical section, taken substantially on the line 2—2 of Fig. 1.

Fig. 3 is a perspective view of one of the improved packing units.

Fig. 4 is a perspective view, on a smaller scale, of a modified form of packing.

Referring first to Figs. 1 and 2, the car journal-box 1 encloses the wedge 2 and brass 3 which rests upon the upper surface of rotating journal 4 formed at the end of car axle 5 which projects into the rear end of box 1 through opening 6. The dust-guard 7 positioned in pocket 8 in the rear wall of the box tends to exclude dust and minimize the escape of oil. The opening 9 in the front end of the box through which packing and lubricant are inserted is normally closed by the lid 10 pivoted to the box at 11.

All of the above is an example of standard construction. Ordinarily the bearing is packed or lubricated by opening the lid 10 and tamping a quantity of loose cotton or wool waste into the space between the bottom of the box and the journal 4. This waste is soaked with oil both before and after its insertion into the box, and additional oil may be added whenever required. Ordinarily a twisted roll of this waste material, known as a "back roll", will first be pushed into place at the rear wall of the box to seal this opening, and after a sufficient quantity of the loose waste has been pushed into place beneath the journal, another compacted mass of the waste known as the "front plug" is often pushed into place at the front of the box. This type of packing is fairly efficient as far as lubrication is concerned, but it has certain faults among which is the frequency of "waste grabs" referred to hereinabove. In order to minimize this evil, it has been necessary to use a fine quality of selected waste from which all of the finer fluffy portions, more apt to be carried up by the rotating journal, have been picked or eliminated, and this greatly increases the cost of the waste material.

According to the present invention, a mass of the loose oil-absorbing material is confined in a flexible fabric bag or envelope so as to form a freely pliant pillow such as shown for example in Fig. 3. In use, a plurality of these units will be used to pack one box, three being shown by way of example in Fig. 1.

The filling or packing material may be cotton or wool waste as indicated at 12 (Fig. 1) and spring inserts 13 or any other suitable resilient

devices are embedded in and distributed as uniformly as possible through the waste for the purposes above mentioned. No particular type of packing material is essential to the present invention, in fact much cheaper grades of waste 5 may be used than has heretofore been the practice since this waste material is effectively confined and cannot find its way between the journal and brass. This mass of waste is confined 10 loosely in a bag or envelope 14 of some suitable cloth fabric sufficiently porous or open in its texture or mesh so that it will be adapted to absorb oil or freely permit the passage of oil there- 15 through but will not permit any strands of waste or lint to pass through it. The bag or envelope is sewed or otherwise secured together in any desired manner, preferably so as not to expose 20 seams or fastening means at the sides more apt to come in contact with the journal. The bag need have no definite form, in fact it is fairly 25 shapeless and pliant so that it may be easily forced into the space beneath the journal. One of these completed units resembles a pillow in its general form, and also in its qualities of pli- 30 ancy and resiliency.

These units or pillows are usually soaked with oil and then drained so that they will be saturated with the lubricant before insertion in the journal box. The units are inserted, one by one, 35 through the front box opening 9, preferably with the longer dimension of the bag extending trans- 40 versely of the box, and then pushed into position between the bottom of the box and the journal as indicated in Figs. 1 and 2. Preferably the units 45 will be of such size that some certain number (for example three) will be sufficient to properly pack a standard car journal box. There is no necessity of providing a separate "back roll" or "front plug", since the functions of these are per- 50 formed by the rear and front pillows or units respectively. The oil will be transmitted in the usual manner from the waste 12 through the envelope 14 to the surface of journal 4. Additional oil can be added in the usual manner, and the bags can be disarranged or pushed into position so as to present new surfaces to the rotating journal.

If desired, a plurality of these bags or units, (enough to pack one journal-box) can be linked 55 together as a chain or series as shown in Fig. 4. A single long bag can be tied at intermediate points 15 and 16 to form a chain of three bags

or links 17, 18 and 19. The links or units of this chain are successively forced into position within the journal-box by bending the series alternately in opposite directions at the joints 16 and 15, in an obvious manner.

In time, the surface of the bag or envelope may 5 wear through, but the enclosed waste material may be reclaimed. If a bag should wear through while in service, no damage will be done since the waste at the sides of the journal is still con- 10 fined and will not be carried up by the journal to cause waste grabs.

This new form of journal-box packing and 15 method of using the same presents numerous advantages over the standard method of packing with loose waste, among which may be mentioned the following: The elimination of waste grabs. Eliminating the necessity of providing separate back rolls and front plugs. Insuring the use of a uniform amount of packing in each box. For- 20 merly the amount of packing used depended upon the judgment of the workman who might use too much or too little. A decrease in the amount of wasted packing material. A cheaper grade of 25 waste may be used. These standard packing units are easier to handle and insert in the box than loose unconfined waste.

I claim:

In combination with a journal and journal box: 30 a packing comprising a plurality of units each 35 consisting of a mass of fibrous, oil absorbent material; a flexible envelope porous and permeable to oil but of a texture to hold the fibrous material and prevent the strands thereof from escaping from the envelope; and a plurality of 40 metallic springs; said units being arranged under the journal transversely thereof with their ends extending upwardly between the sides of the journal box and the journal and so that the pack- 45 ing substantially fills the space between the bot- 50 tom and sides of the journal box and the portion of the journal below its center and fits closely and continuously around the under side of the journal, and said springs being embedded in and distributed with substantial uniformity through- 55 out the fibrous material so as to keep the material open and loose against matting and ex- 60 panded in contact with the envelope, and so as to keep the envelope pressed with substantial uni- 65 formity against the journal.

CHARLES T. RIPLEY.
